UNITED STATES PATENT OFFICE.

JOSEPH D. INGRAM, OF AMARILLO, TEXAS.

ENGINE.

1,393,785.

Specification of Letters Patent.

Patented Oct. 18, 1921.

Application filed February 7, 1920. Serial No. 357,007.

To all whom it may concern:

Be it known that I, JOSEPH DAN INGRAM, a citizen of the United States, residing at Amarillo, in the county of Potter and State 5 of Texas, have invented a new and useful Engine, of which the following is a specification.

This invention relates to engines of that type having radially disposed cylinders, one 10 of the objects of the invention being to provide means whereby a pair of cylinders may utilize the full bearing surface of a single crank, the piston rods being connected together and mounted on the bearing in a 15 novel manner and being so disposed relative to each other as to relieve the dead center and materially increase the crank power without lengthening the piston travel.

With the foregoing and other objects in 20 view, which will appear as the description proceeds, the invention resides in the combination and arrangement of parts and in the details of construction hereinafter described and claimed, it being understood 25 that, within the scope of what is claimed, changes in the precise embodiment of the invention shown can be made without departing from the spirit of the invention.

In the accompanying drawing the pre- 30 ferred form of the invention has been shown.

In said drawings

Figure 1 is a section through a portion 35 of an engine having the present improvement.

Fig. 2 is a section on line 2—2, Fig. 1.

Fig. 3 is a detail view of the ball end of one of the piston rods.

Referring to the figures by characters of reference 1 and 2 designate cylinders of an 40 engine of the V-type and the pistons 3 and 4 therein have rods 5 and 6 respectively connected thereto. The piston rod 5 is provided at its lower end with an arcuate bearing member or yoke 7 the terminals of 45 which are adapted to receive bolts 8 which serve to fasten a cap 9 to the yoke 7, said cap and yoke co-operating to form a complete bearing member adapted to extend around the crank pin P of the shaft S. The 50 piston rod 5 is formed integral with the yoke 7 and is disposed close to one end thereof and formed in the yoke preferably midway between said rod 5 and the other end of the

yoke is a recess 10 provided with a bearing plate 11 of any suitable material and which 55 fits snugly in the recess. This plate is adapted to be engaged by a ball 12 formed integral with a neck 13 located at the lower end of the piston rod 6. A retaining cap 14 has one end portion fastened to the yoke 7 by 60 one of the bolts 8. The other end portion of this cap 14 is slotted, as indicated at 15 and the neck 13 extends through the slot. The said cap 14 is recessed so as to fit upon the ball 12 and that end of the cap 14 remote 65 from the bolt 8 is pivotally connected, as at 16, to an ear 17 formed in the angle between the piston rod 5 and the yoke 7.

Importance is attached to the particular construction described and shown because it 70 allows the two pistons to be coupled to one crank and, by mounting ball 12 toward rod 5 in the direction of travel the dead center of rod 6 is overcome and the crank power of piston 4 is materially increased without 75 necessitating lengthening the stroke of the piston.

It will also be noted that wear upon the ball 12 and its bearing surfaces can be taken up readily simply by adjusting the bolt 8 80 which serves to connect the cap 9 at one end to the yoke 7. Thus the parts are reduced to the minimum. Wear upon the parts 9 and 7 can be taken up by removing one or more shims 18 which are interposed between 85 said parts 7 and 9 and upon the bolt 8. Shims can also be removed when it is desired to adjust the cap 14 relative to the yoke 7.

It will be apparent that as the piston rods 90 5 and 6 move practically in unison and have very slight relative movement, practically all of the wear resulting from the operation of this apparatus takes place between the parts 7 and 9 and the crank engaged thereby. 95

What is claimed is:

1. In an engine the combination with a crank engaging yoke and a piston rod integral therewith, of another piston rod pivotally connected to the yoke, the two rods 100 being mounted to work in the same plane, and separate means engaged by a single bolt for holding the yoke upon a crank and for holding the pivoted piston rod to the yoke.
2. The combination with a crank engag- 105 ing element and a piston rod integral there-

with and radiating therefrom, of a second piston rod movably connected to said element and adapted to work in the same plane with the first named piston rod, and adjustably mounted retaining means carried by said element and holding the movable piston rod thereto.

In testimony that I claim the foregoing as my own, I have hereto affixed my signature in the presence of two witnesses.

JOSEPH D. INGRAM.
